UNITED STATES PATENT OFFICE.

CHARLES W. McGARY, OF EVERETT, MASSACHUSETTS, ASSIGNOR OF ONE-HALF TO
HERBERT L. HILDRETH, OF BOSTON, MASSACHUSETTS.

INTERNAL-COMBUSTION ENGINE.

1,099,856.

Specification of Letters Patent. Patented June 9, 1914.

Application filed April 30, 1910. Serial No. 558,681.

To all whom it may concern:

Be it known that I, CHARLES W. McGARY, a citizen of the United States, residing at Everett, in the county of Middlesex and State of Massachusetts, have invented a certain new and useful Improvement in Internal-Combustion Engines, of which the following is a specification, reference being had therein to the accompanying drawings.

10 My present invention has for its object an improvement in internal combustion engines, otherwise known as gasolene explosion engines, and more particularly the so-called two-cycle type of engine. Heretofore in the manufacture of engines of this general class and type it has been customary to employ a closed crank case in which the explosive mixture of gas and air is compressed prior to its admission to the cylinder. While there have been some engines of the two-cycle type in which the closed crank case is not employed, it has ordinarily been considered impracticable to construct two-cycle engines without a closed crank case.

25 By the employment of my invention the closed crank case may be omitted and an open crank case may be employed if desired. The omission of the closed crank case does away with all the difficulties arising from leakage through the joints of the crank case and about the bearings; makes it possible to supply the cylinders with a mixture which does not contain any spray or vapor of oil; avoids the presence of grit

30 in the crank case introduced through the carburetor; makes it possible to employ a better system of lubrication for the pistons and bearings; and, also, does away with the difficulty of designing a crank case, the con-

35 tent of which shall bear the proper relation to the content of the cylinder so that the proper degree of compression may be obtained.

The important feature of my invention which enables me to do away with the so-called closed crank case is the placing of a compressor of peculiar structure between the carburetor and the cylinders of the engine so that the mixture of gas and air is compressed by the compressor before it is introduced into the cylinder. This enables the cylinders to receive at all speeds a full charge of fresh gas. In closed crank case engines of the two-cycle type, it is found

50 that there is a certain speed at which the

crank case will be filled on each revolution with the fresh gas, but when the engine exceeds that speed a less charge is drawn in owing to the inertia of the gas.

In the engine embodying my present invention, the cylinder receives at each revolution a full charge of gas as the gas is driven into the cylinder by the compressor. Furthermore, the speed of the compressor is in general increased with any increase in the speed of the engine, and consequently increases the force by which the gas is driven through the ports into the cylinders so that the inertia of the gas has no perceptible effect on the operation of the engine.

Another important feature of my invention consists in governing the speed and power developed by the engine by varying the speed of the air compressor and consequently the amount of compressed gas which is introduced into the cylinders as a charge.

As is well known to those skilled in this art the two-cycle engine furnishes a more continuous supply of power and consequently a more continuous turning force upon the crank and shaft than the four-cycle engine, but the difficulties attendant upon the use of the closed crank case or its substitutes and the difficulty of obtaining perfect scavenging of the cylinders have made the two-cycle engine unpopular. My present invention does away with these difficulties to a large extent and affords an engine which retains all the well known advantages of the two-cycle engine as well as many of the advantages of the four-cycle engine. It may be controlled and operated with greater ease than any other engine heretofore known to me.

While I have shown and described my invention as embodied in an automobile engine, it is obvious that it may be used for marine or stationary purposes as well as for the propulsion of motor vehicles and also that it is capable of various modifications and changes all within the spirit of my invention.

The invention will be fully understood from the following description taken in connection with the accompanying drawings, and the novel features will be pointed out and clearly defined in the claims at the close of the specification.

In the drawings,—Figure 1 is a front elevation of an engine embodying my invention. Fig. 2 is a top plan view of the engine shown in Fig. 1. Fig. 3 is a longitudinal section 5 of the engine on line 3—3 Fig. 1. Fig. 4 is a transverse section of the engine and the upper part of the crank case. Fig. 5 is a section on line 5—5 Fig. 4. Fig. 6 is a section on line 6—6 Fig. 1. Fig. 7 is an end view of 10 the clutch and governor by means of which the speed of the compressor is controlled. Fig. 8 is a section on line 8—8 of Fig. 6. Fig. 9 is a detail of the clutch forming a part of 15 the governor. Fig. 10 is a detail partly in section of the air timer by means of which the compressed air operating the self starting mechanism is distributed to the cylinders. Fig. 11 is a section on line 11—11 of 20 Fig. 10. Fig. 12 is a detail showing the construction of the spring packing rib in the piston.

Referring now to the drawings and more particularly to Figs. 1, 2, 3 and 4, there will be seen at A and B the two frangs by means 25 of which the engine is supported in the body of the vehicle. The cylinder castings are shown at C and the crank case at D. The crank is designated E and the fly wheel F. Except as hereinafter mentioned these parts 30 are of ordinary construction.

At G, is indicated a carbureter or other device for producing an explosive mixture of air and gasoline or other hydrocarbon fuel.

While I have described a carbureter as one 25 element of the combination comprising my invention, I do not limit myself to that form of carbureter in which a mixture of air and liquid hydrocarbon is made, but intend that the term carbureter shall also include any 40 device in which an explosive mixture of air and hydrocarbon is produced, such for instance as a mixture of air and producer gas.

The carbureter G is connected by a pipe 11 with a compressor 12 by means of which 45 the explosive mixture is compressed and introduced into the cylinder. The compressor 12 may be of any well known construction, but I prefer to employ a compressor like that shown and described in the application 50 for United States Letters Patent filed by me, January 28, 1910, Serial No. 540,490. This compressor consists of a casing 13, in which are located two rotating members 14 and 15. The upper rotating member is 55 driven by a gear 16 meshing with gear 17 on the shaft of the lower rotating member 15, and the lower member is itself driven by a gear 18 meshing with a gear 19 on the main shaft. The two rotating members 14 and 15 60 of the compressor are male and female being furnished with pockets and teeth respectively and are so constructed that the two rotors are always in contact with each other as they revolve, the root circle of one rotor being in contact with the addendum circle of the other

rotor. The walls of the pockets and teeth are in cross-section shaped like gear teeth but of a peculiar construction such that the point of contact between the two rotors progresses along the root circle of the male rotor, up the 70 side of the tooth, along the point of the tooth, down the other side of the tooth and again along the root circle toward the next tooth. It will be seen that as the said rotors revolve, the mixture of gas and air is carried in by the 75 pockets 151 in the rotor 15, compressed to the density of the mixture on the discharge side of the compressor, and discharged into the cylinders of the engine. The compressor of the peculiar construction shown and de- 80 scribed herein permits only a minimum of the compressed mixture to escape to the inlet side of the compressor and, therefore, insures the production of a degree of compres- 85 sion varying with the speed at which the rotors are driven.

The mixture of gas and air is sucked in through the port 20 and discharged through the ports 21 and 22 which lead into the cylinders. The port 22 is located directly op- 90 posite the exhaust port 23 through which the burnt gases escape and as low down in the cylinder as possible and yet be uncovered by the piston at the extreme lowest point of its stroke. Since the fresh gas is introduced 95 into the cylinder under relatively high pressure, it serves not only to fill the cylinder completely but also tends to drive out the burned gases left from the previous explosion.

The piston 24 is furnished at 25 with a baffle plate of peculiar construction which extends upwardly from the end of the piston. This baffle plate 25 may be plainly seen in Figs. 4 and 5. It has a circular wall 251 105 and is provided with radial ribs 26 which divide the space into pockets. Two of these ribs 26, 26, register with two of the bars 27 which strengthen the walls of the cylinder at the inlet port 22. The baffle plate is of a 110 height about as great as can be employed and not strike the cylinder head so that it forms a sort of firing chamber in which the first explosion of gas takes place. The baffle plate 25 forms a guide which directs the 115 fresh gases upwardly toward the head of the cylinder and also prevents the fresh gas from rushing out of the exhaust port which is opened at the same time as the inlet port. The spark plug 28, by means of which the ex- 120 plosive mixture is fired, is located directly above one of the pockets formed by the baffle plate 25 and its ribs 26. By this arrangement I find that a certain portion of the new gas is carried upward with the piston, re- 125 maining in the pocket therein, and surrounds the spark plug at the time when the spark is discharged into the explosive mixture. The spark ignites this fresh gas more readily than as if it were mixed with the 130

exhaust gases in the cylinder, and makes it possible to obtain an explosion in the cylinder under conditions under which ordinarily no explosion would be produced.

In practice, I have found that the portion of gas inclosed by the baffle plate will explode even when the amount admitted to the cylinder has not been sufficient to form an explosive mixture in the main portion of the cylinder. It also results that at all times a more complete explosion is obtained as the gas in the pocket of the baffle plate fires easily and communicates the explosion to the mixture contained in the other portions of the cylinder.

The piston 24 is provided with the ordinary horizontal piston rings 29 and also with two vertical ribs 30 (see Figs. 3 and 5) which are located one on each side of the inlet ports 22 and contact with the walls of the cylinder so that it is not possible for the new gas which is under pressure in the compressor to rush around the piston and escape through the exhaust port or be prematurely ignited. These vertical ribs effectively protect the inlet port and prevent any of the gases under pressure in the inlet port escaping around the piston to the exhaust port. This is important as the gas in the inlet port is under pressure during the entire stroke of the piston and without this protection there would be leakage into the exhaust.

The lubricating system will now be described.

On the main shaft H is carried a disk 31, the lower edge of which dips in oil contained in the lower part of the crank case D. The oil picked up by the disk 31 is thrown off violently and spattered in all directions. The oil which is splashed by the disk 31 and thrown against the walls of the crank case runs down into grooved ledges 32 and 33 and then through the ports 34 into oil wells 35 at the main bearings of the shaft. Over the main shaft H and in the oil well 35, is hung a chain 36 which serves to dip up oil from the oil well and pour it over the main shaft in the center of the main bearing. In this manner the main bearing is thoroughly lubricated. Oil from the oil well 35 is carried to each crank bearing by means of a duct 37 formed in the crank and so constructed that the centrifugal force developed in the oil by the rotation of the crank causes the oil to flow from the oil well 35 to the crank bearing.

The grooved oil ledge 32 is made to slope from the center toward the ends of the crank case so that the oil will constantly flow into the oil wells even though the engine is tilted, as for instance would be the case in an automobile on a grade or in a boat not trimmed on an even keel. Under these circumstances, if the ledge 32 were

horizontal, one oil well or the other might not be furnished with a sufficient amount of oil and the bearing which it lubricates might possibly run dry. The construction shown effectively prevents this.

The piston 24 is constructed so that it projects below the bottom of the cylinder when it is at the end of its stroke. A groove 201 of peculiar ratchet shape is formed in the piston in such a position that it is uncovered at the end of the stroke. For convenience, I have termed this groove ratchet shaped, thereby intending to convey the meaning that it is cut at an angle downward. This groove receives oil from the splash in the crank case. As the piston moves up into the cylinder, the oil is carried up in the groove, the inertia of the oil tending to hold it in the bottom of the groove. On the return stroke, the oil is displaced from the groove by movement of the piston and is distributed over the walls of the cylinder and piston. This construction effectively lubricates the piston and cylinder.

The speed and power which is developed by the engine is controlled in the following manner. As has been previously stated, the compressor is driven from a gear 19 on the main shaft. The speed of the compressor and consequently the amount of the charge introduced into the cylinders and the density to which it is compressed is varied by means of a governor, which will now be described. This governor is carried by the compressor and operates to cause the compressor to run at a constant speed determined by the point at which the governor is set by the operator.

A gear 19 on the main shaft H meshes with an idle gear 18 which itself meshes with a gear 39 which is loose on sleeve 40. The sleeve 40 incloses the shaft 41 of the lower rotor 15 of the compressor and the two are fast to each other. The gear 39 revolves in a bearing on the sleeve 40 and is formed integral with a clutch ring 42, within which are located two clutch members 43 and 44 which are movable toward and away from the center of rotation to engage or disengage with the inner surface of the clutch ring 42. On the sleeve 40, there is fast a frame or spider 45 which supports two or more governor levers 46 and 47. Said levers 46 and 47 are pivoted to lugs on the spider 45 at 48 and 49 respectively and carry on their outer ends weights 50 and 51 respectively. These weights 50 and 51 are of a weight sufficient to operate the governor and are of flattened form as shown in Figs. 6 and 8, this being the form which is most convenient to inclose in the governor casing 52. The inner ends of the governor levers 46 and 47 are forked as shown at 54 and 55 and the forks engage pins 56 and 57 carried between pairs of lugs 58, 59, 60 and 61 respectively on two movable clutch members 130

43 and 44. The sliding movement of the clutch member 43 is guided by two studs 62 fast in the spider 45 while the clutch member 44 is guided on two similar studs 63. 5 These studs operate in slots 64 in the clutch members. From the foregoing, it will be seen, that, if the clutch members 43 and 44 are moved outwardly, they will engage the inner surface of the clutch ring 42, and will 10 be caused to turn with it. If the pressure is sufficient, the clutch ring and the clutch members will rotate together with the same speed, but if the clutch members are held less firmly against the clutch ring some slip 15 will occur and the interior clutch member will rotate at a proportionately less speed than the clutch ring. By varying the pressure with which the interior clutch members are held against the clutch ring the speed 20 of the clutch ring and its attached parts may be varied as desired.

On the clutch levers 46 and 47, are located projections 65 and 66 which extend radially toward the sleeve 40. Against these projections, rests a ball-bearing collar 67 which is pressed toward them by means of a spring 68, the other end of which rests against a collar 69 which is slideable longitudinally of the sleeve 40 by means of the lever 70 on the 25 shaft 71. The shaft 71 is operated in any convenient manner as for instance by the crank 72 and connecting rod 73 (see Fig. 2). A movement of the connecting rod 73 in one direction causes the collar 69 to be moved to 30 the left (see Fig. 6) and to compress the spring 68 against the ball bearing collar 67 which itself rests against the governor levers 46 and 47. The effect of this pressure upon the governor levers is to move the 35 clutch members 43 and 44 outward, and cause them to engage the clutch ring more forcibly, thereby causing the sleeve and attached parts to rotate at more nearly the speed of the gear 19. Thereafter until the 40 governor is set again, the compressor will be run at a constant speed (within certain limits) regardless of the speed at which the engine runs. The engine will, therefore, receive a constant charge from the 45 compressor at each stroke and will run at whatever speed the explosion of that charge will produce under the load at which the engine may be running at that instant. It is found in actual practice that the engine maintains 50 a speed which is very nearly constant for any given position of the governor and that change in load produces slight variation in speed.

When it is desired to change the speed of 55 the engine, the connecting rod 73 is moved the required amount. This sets the governor at a new point, and thereafter the compressor will be run at a new speed which is substantially constant regardless of the 60 speed of the engine. It will thus be seen

that an important feature of this part of my invention is the application of a governor to the compressor thereby controlling the speed of the compressor and consequently the charge delivered to the engine. It will 70 also be understood that any form of governor which will control the speed of the compressor may be employed. The form shown in the drawings is a satisfactory one.

The self starting devices by means of 75 which the laborious operation of cranking the engine is avoided will now be described. They consist primarily in means for supplying to the respective cylinders at proper times in their cycle of rotation, a sufficient 80 supply of compressed air to cause the engine to turn over until an explosion has been obtained by ignition of a charge of gas in one of the cylinders.

In Fig. 2 there will be seen a compressed 85 air tank 74 connected by the pipe 75 to the air distributor 76. The air distributor consists of a rotary valve 77 mounted on shaft 78. Said shaft 78 is rotated by a pair of spiral gears 79 and 80, the latter of which 90 is located upon the main shaft H, which also operates the electric timer 182. Two pipes 82 and 83 lead from the air distributor 76 to the tops of the two cylinders C of the engine. The rotary valve 77 of the air distributor in the form shown in the drawings is cut away on one side as shown at 84, Fig. 11, for an angular space of about one hundred twenty degrees. The air from the air tank 74 is admitted successively by the 100 rotary air valve 77 to the pipes 82 and 83 for a length of time determined by the size of the cut away space 84. This length of time is long enough to give the piston and fly wheel momentum sufficient to carry them by the center. On the top of each of the cylinders C is located a valve 86 (see Fig. 3) which closes the head of the cylinder during the ordinary operation of the engine, but opens it to admit the compressed 105 air when the self starting device is put in operation. The valve 86 is contained within a casing 85, and contacts with a seat in the said casing, being normally held in contact therewith by means of a spring 87. 110 The casing 85 is closed at its top by means of a cap 88 and one of the pipes 82 and 83 is connected to the casing. The supply of compressed air to the air distributor is controlled by means of the valve 89. This 115 valve is opened when it is desired to start the engine and is closed again after the ordinary operation of the engine has begun. The compressed air carries the piston down with it until the exhaust port is opened. 120 At about this time the air distributor shuts off the supply of compressed air and the compressed air then within the cylinder begins to escape through the exhaust port. This reduces the pressure in the cylinder 130.

and in the pipe so that the valve 86 is closed by the spring 87. The cylinder then receives its charge of gas through the inlet port in the ordinary way.

5 While I have described my invention as embodied in an internal combustion engine of the two-cycle type, I believe that many features of it are applicable to four-cycle engines.

10 What I claim is:—

1. In an engine of the character described, the combination with a cylinder and piston of a carbureter and a rotary compressor receiving a mixture from the carbureter, and 15 discharging it into the cylinder and means for varying the speed of the compressor whereby the charge delivered to the engine by the compressor is varied, said means for varying the speed of the compressor consisting of a rotary clutch ring, means for rotating the said clutch ring, friction clutch members connected with the compressor so as to rotate therewith and movable with relation to said clutch ring, pivoted levers engaging with 25 said movable clutch members, tension mechanism for pressing said levers with yielding pressure against said movable clutch members, and thereby pressing said clutch members into yielding frictional engagement 30 with said clutch ring.

2. In an engine of the character described, the combination with a cylinder and piston of a carbureter and a rotary compressor receiving a mixture from the carbureter, and 35 discharging it into the cylinder and means for varying the speed of the compressor whereby the charge delivered to the engine by the compressor is varied, said means for varying the speed of the compressor consisting of a rotary clutch ring, means for rotating the clutch ring, friction clutch members connected with the compressor so as to rotate therewith, and movable with relation to said clutch ring, pivoted levers engaging 40 with said movable clutch members, tension mechanism for pressing said levers with yielding pressure against said movable clutch members, and thereby pressing said clutch members into yielding frictional engagement 45 with said clutch ring, and means for varying the tension of the tension mechanism.

3. In an engine of the character described, the combination with a cylinder and piston

of a carbureter and a rotary compressor receiving a mixture from the carbureter and discharging it into the cylinder and means for varying the speed of the compressor whereby the charge delivered to the engine by the compressor is varied, said means for varying the speed of the compressor consisting of driving mechanism, a rotary clutch ring actuated by said driving mechanism, a rotary shaft on which said compressor is mounted so as to rotate therewith, a frame also mounted on the compressor shaft so as to rotate therewith, levers pivoted to said frame, friction clutch members engaged by said levers and rotatable with said compressor and movable toward and from said clutch ring and adapted to engage frictionally with said clutch ring and tension mechanism whereby the said movable clutch members are actuated through the levers to engage with yielding pressure against the said clutch ring.

4. In an engine of the character described, the combination with a cylinder and piston of a carbureter and a rotary compressor receiving a mixture from the carbureter, and 80 discharging it into the cylinder and means for varying the speed of the compressor whereby the charge delivered to the engine by the compressor is varied, said means for varying the speed of the compressor consisting of driving mechanism, a rotary clutch ring actuated by said driving mechanism, a rotary shaft on which said compressor is mounted so as to rotate therewith, a frame also mounted fast on the compressor shaft 90 so as to rotate therewith, levers pivoted to said frame, friction clutch members engaged by said levers and rotatable with said compressor and movable toward and from said clutch ring and adapted to engage frictionally with said clutch ring and tension mechanism whereby the said movable clutch members are actuated through the levers to engage with yielding pressure against the said clutch ring and means for adjusting 95 said tension mechanism.

In testimony whereof I affix my signature, in presence of two witnesses.

CHARLES W. McGARY.
